UNITED STATES PATENT OFFICE

2,472,543

RADIAL-FLOW TURBINE OF DOUBLE
ROTATION TYPE

Ragnar Olov Jacob Möller, Finspong, Sweden

Application December 10, 1943, Serial No. 513,743
In Germany December 11, 1942

1 Claim. (Cl. 253—16.5)

1

The present invention relates to elastic fluid turbines of the radial flow type having blades and discs rotating in opposite directions.

It is a well-known fact that in this type of turbine great leakage losses appear between the individual blade rings resulting in a reduction of the efficiency. Several proposals have been made in order to overcome this difficulty. According to one proposal the turbine is used as the main part of a combined turbine also including an auxiliary turbine of the impulse type. By this means a considerably higher efficiency of the turbine aggregate as a whole may be obtained due to the fact that the impulse turbine when driven by steam or other elastic fluid of high pressure and great velocity develops a higher efficiency than a turbine operating on the reaction principle. By the term "impulse" turbine is meant a turbine in which the driving fluid acts as a positive impeller. Amongst other advantages obtained by this combination of an impulse turbine and a reaction turbine, it is to be noted that the stationary nozzles belonging to the impulse turbine are subjected to less leakage losses and permit a partial governing (partial admission) whereby small losses are obtained as compared with those resulting from the hitherto almost exclusively used throttling or stage governing method. The impulse turbine yields a great initial expansion and a resulting great drop of pressure and temperature in its nozzles. As a result the reaction turbine will not be subjected to the high initial pressure and the high initial temperature of the driving fluid, as steam. The partial admission as used in connection with the action turbine requires longer blades resulting in an increased efficiency.

The advantages of the combination above referred to of an auxiliary turbine of the impulse type and a radial flow main turbine of the reaction type depend exclusively on the use of an impulse turbine as auxiliary turbine. The radial flow turbine itself, however, does not undergo any improvement, but rather an impairment, owing to the fact that the steam discharged from the impulse turbine flows from outside inwardly through the radial flow turbine. The highest drops of pressure and temperature of the radial flow turbine will thus take place in the widest blade rings where the greatest losses appear.

The object of the invention is to provide a combined turbine comprising an auxiliary impulse turbine and a radial flow main turbine of the reaction type in which combination also the reaction turbine assists in increasing the effi-

2

ciency and improving the qualities and the effect of the turbine plant as a whole.

To this end the radial flow turbine which is of the double rotation type is provided with two or more axially spaced blade groups so arranged with reference to the impulse turbine as to be passed in series by the driving fluid discharged from the impulse turbine, the first group of the series being so situated as to be traversed by the fluid while flowing from inside outwardly. Thus, the driving fluid discharged from the impulse turbine undergoes its greatest drop of pressure and temperature in that portion of the blading where the smallest losses appear. Consequently, the losses of the turbine plant will become less than those of the known combined turbines in which, as already mentioned, the driving fluid does first flow through the blade rings of the radial flow turbine having the largest diameter. Moreover, the radial extension of the blading of the reaction turbine will become considerably less than that of a turbine having but a single or unitary blading, and the losses of the reaction turbine are reduced accordingly. The same comment applies also to the leakage losses appearing in the labyrinth packings and the shaft packings. All of the above stated circumstances assist in improving the efficiency.

30 In the accompanying drawing two embodiments of the invention are illustrated.

Fig. 1 is an axial section of part of a turbine according to one embodiment, and Fig. 2 is a diagrammatic axial section of part of a turbine according to the other embodiment.

35 With reference to Fig. 1, the reference numerals 1 and 2 designate the two turbine shafts adapted for opposite rotation. Keyed to the shaft 1 are two axially spaced turbine discs 3 and 4. The disc 3 represents one, viz. the left hand, extreme disc of the turbine rotor, while disc 4 is located nearly in the middle of the rotor. The turbine shaft 2 supports a turbine disc 5 representing the other, viz. the right hand, extreme disc of the turbine rotor. By means of a drum-shaped connecting member 6 fastened to the outer periphery of disc 5, the latter carries an inwardly projecting turbine disc 7 located in the space between the turbine discs 3 and 4. The turbine discs 3 and 7 project rather far beyond the periphery of the drum 6. At its outer periphery the disc 3 carries a set of impulse blades 8, and at a somewhat smaller diameter the disc 7 carries a corresponding set of impulse blades 9. 50 It is to be noted that, of course, more than two

sets of impulse blades may be provided between the turbine discs 3 and 7.

On their sides facing each other the turbine discs 7 and 4 carry a group of blades 10 for radial admission of the driving fluid. The opposite surfaces of the discs 4 and 5 carry similarly another group of blades 11 for radial admission.

Provided in the portion of stationary turbine casing 12 surrounding the blade rings 8 and 9 is a set of nozzles 13, through which the driving fluid, as for instance steam, is admitted to the outermost ring of impulse blades 8, causing said ring to rotate in a definite direction. The driving fluid as discharged from the blade ring 8 impels the blade ring 9, causing it to rotate too, though in the opposite direction. The driving fluid as discharged from the blades 9 flows inwardly through the passage 14 formed between the turbine discs 3 and 7, as indicated by an arrow, and enters at the inner end of said passage the axial passage 15 by which it is conveyed to the blade group 10 through which the fluid passes from inside outwardly. The fluid as discharged from the blade group 10 at the outer periphery thereof is conveyed by the axial passage inside the cylindrical wall 6 to the outer periphery of blade group 11 through which the fluid flows inwardly to be then finally discharged from the turbine through the ports 16, 17 formed in the turbine discs 3, 4 and 5 and the associated outlet pipes 18, 19. As the outlet ports 16 and 17 are located at a very small distance from the turbine axis, the leakage losses along the turbine shafts become very small.

At appropriate points, as for instance, axially outside the turbine discs 3 and 5, labyrinth packings as 20 and 21 may be provided.

If desired, blade rings for radial admission may also be provided in the spaces between the turbine discs 3 and 7, as indicated at 22.

The outer portions of the turbine discs 3 and 7 are formed with ports 23 and 24, respectively, through which steam for balancing purposes may be admitted to the labyrinth packings 20 and 21, respectively; the axial thrusts acting on the outermost portions of the discs 3, 7 however, balance each other.

In the embodiment above described, the driving fluid passes from outside inwardly through the blade rings 8 and 9 of the auxiliary impulse turbine. It is to be noted that the reversed direction of flow may be used, though only when the impulse turbine comprises but one blade ring. An embodiment of a corresponding turbine is indicated in Fig. 2. The driving fluid flows in the direction indicated by arrows, that is to say, it is admitted by the stationary inlet 25 to the single blade ring 26 of the impulse turbine and is conveyed when discharged therefrom, by the stationary reversing conduit 27 to the passage between the turbine discs 3 and 7 at the inner end of which the fluid alters its direction of flow and enters the blade group 10 to then pass through the turbine in the way already described.

What I claim is:

A turbine unit comprising a double rotation

radial flow turbine having two shafts for opposite rotation, two groups of axially spaced radial discs alternately arranged with relation to each other so that at least one disc of each group forms a baffle between two discs of the other group, the discs of one group all being supported at their inner peripheries by one shaft, while only one disc of the other group is directly supported at its inner periphery by the other shaft, a cylindrical member for connecting an outer point of another disc of said other group to said directly supported disc, so that the discs and said cylindrical member form a convolute passage comprising a set of radially extending channels between the discs for traverse successively by elastic driving fluid, turbine blades in said channels supported alternately by one and the other of the respective discs, the blades in the first radial channel in order of fluid flow which is adapted to be traversed by the driving fluid from outside inwardly being a set of impulse turbine blades located at the outer end portion of said first channel, the subsequently traversed radial channels each being provided with a group of reaction turbine blades mounted on the respective discs, the first of said groups of reaction blades being arranged to be traversed by fluid passing outwardly and the last group by fluid passing inwardly, so that the driving fluid is delivered from the blade system in proximity to the turbine axis, a stationary casing enclosing said discs and blades, labyrinth packings sealing said discs and blades in said casing, the discs carrying the impulse blades being of a larger diameter than the remaining discs, the projecting portions of said larger discs being exposed to passages leading to the outer periphery of said packings and being formed with ports for allowing fluid that has passed the impulse blade system to reach the outer ends of the labyrinth packings for balancing purposes.
